HOLLOW BLAST REVOLVING GRATE.

No. 595,649.

Patented Dec. 14, 1897.

UNITED STATES PATENT OFFICE.

WALTER E. PAYNE AND FREDERIC L. JOUBERT, OF NEW ORLEANS,
LOUISIANA.

HOLLOW BLAST REVOLUBLE GRATE.

SPECIFICATION forming part of Letters Patent No. 595,649, dated December 14, 1897.

Application filed November 20, 1896. Serial No. 612,853. (No model.)

To all whom it may concern:

Be it known that we, WALTER E. PAYNE and FREDERIC L. JOUBERT, citizens of the United States, residing at New Orleans, in 5 the parish of Orleans and State of Louisiana, have invented a new and useful Improvement in Hollow Blast Revoluble Grates, of which the following is a specification.

Our invention relates to such furnaces or 10 ovens as are used in connection with the manufacture of sugar from the different varieties of the sugar-cane, the saccharine juices having first been extracted therefrom by a suitable process, the resulting residue known 15 as "bagasse" being thereby rendered available for utilization as fuel in generating steam; and the objects of our invention are to provide a fire-grate to form a part of such furnaces as will permit of the application of a 20 forced blast of air directly to the bagasse upon the grate without intervening obstacles, thereby producing a more intimate combination and a more thorough mixture of the resulting gases of combustion, and to construct 25 a grate facilitating access to all its parts for repairs thereto and for the removal of ashes and slag. We attain these objects by the construction shown in the following drawings, in which—

30 Figure 1 is a plan of the grate, showing a portion thereof with the grate-bars in position. Fig. 2 is a vertical section through the same on the line A A. Fig. 3 is a plan of one of the hollow blast grate-bars which we employ. Fig. 4 is a section through the same on line B B. Fig. 5 is a section through same on the line C C. Fig. 6 is a section through same on the line D D. Fig. 7 is a plan of one of our plain grate-bars. Fig. 8 is an elevation 35 of the same. Fig. 9 is a section through one of the hollow radial arms g on the line E E. Fig. 10 is a plan of the same. Fig. 11 is a section through the radial arm g on the line F F. Fig. 12 is a plan of the central blast-plate. Fig. 13 is a section through the 40 same. Fig. 14 is an elevation of the central hand-hole cover. Fig. 15 is a plan of the same. Fig. 16 is a plan of the grate.

Similar parts are designated by the same 45 letters throughout the different views.

The blast is introduced through the pipe a,

passing thence into the central post b, which, with the rim-rollers c, placed at intervals around the periphery of grate, supports the entire construction. The post b is bolted to 55 the base-plate d, which is itself anchored to the foundation at the center of the furnace and sufficiently far below the surface of the ash-pit to allow the blast-pipe to be connected to the post b without obstructing the ash-pit. 60 At a convenient distance below its upper end the post b is provided with a grooved collar. The slotted cylinder e is flanged at its lower end and is recessed throughout a part of its length to receive the projecting end of the 65 post b above its collar, the engaging surfaces being turned perfectly true, thereby insuring an air-tight joint.

The flange on cylinder e is grooved correspondingly to the collar on b, and a sufficient 70 number of perfectly-spherical balls f are placed between them, permitting the grate to be turned with a minimum of effort at the crank t. The radial arms g are bolted to the outer surface of the cylinder e, their outer 75 ends being flanged at the top and bottom, the lower flanges carrying a circular rack and rail h and the upper flanges bearing a circular rail j to support the outer ends of the grate-bars. The intermediate rail k is provided with an 80 additional support for the grate-bars. The radial arms g are provided with a hollow box at their inner ends, each having a hollow branch on either side, each one of these branches being fitted to the under side of one 85 of the hollow grate-bars l and fastened thereto with bolts, making an air-tight joint. The hollow grate-bars l are of a rectangular section and conform to a segment of a circle, having a branch extending to either side at its widest 90 end. As shown in Figs. 5 and 6, the sides are perforated near the upper corners, these perforations occurring at all edges, excepting the small end toward the center of grate and at the ends of the two projecting branches. 95 These perforations occur at intervals, they being so disposed as to distribute the air-blasts equally to all parts of the grate.

By inspecting Fig. 1 it will be seen that the outer periphery of the grate is entirely formed 100 by the hollow blast-bars l, and the object of this being to completely encircle the grate

with an upward blast of air, thereby preventing the adhesion of the grate to the interior surface of the furnace, due to fluid vitreous matter resulting from the combustion of the bagasse.

5 In order to produce a further distribution of the blast, each hollow bar is provided with perforated recesses, these being partially filled by a circular piece *m*, bolted to the bar, 10 this piece being of smaller diameter to permit of the passage of the blast and at the same time preventing the recess being filled with dirt. The slotted grate-bars *n* fill up the spaces between the hollow bars *l* and are provided with lugs on each side and at the outer end, these lugs insuring a uniform space between the edges of the hollow and the slotted bars, through which the blast reaches the surface of the grate. The purpose of the slotted 15 bars is to allow the ashes and other residue of being raked and precipitated to the ash-pit below. The central blast-plate *p* completes the surface of the grate and is bolted to the upper end of the cylinder *e*, a narrow space 20 being left between the edge of the plate *p* and the inner ends of the grate-bars to permit of the passage of the blast from the perforations in the crown of plate *p*. At the center of this 25 plate is a hand-hole encircled with a perforated crown similar to that at the outer edge. At the lower edge of this crown and on its inner surface is a continuous collar, which serves as a rest for the hand-hole cover-piece *r*, this piece being dropped in position through the 30 wards in the upper collar and locked in position by the engagement of the wards in the cross-ribs between the two disks, forming part of cover-piece *r*, a partial turn sufficing 35 to lock them together.

40 At the outer edges of the cover-piece are formed a sufficient number of projections to insure a narrow opening for the discharge of the blast. The disk at the bottom of the cover-piece overlaps the lower collar on the 45 crown and prevents the escape of air through the hand-hole. At the outer side of the upper disk of cover-piece *r* several recesses are 50 formed to engage corresponding pins on a key or turning-wrench when it becomes necessary to remove the cover.

The combination pinion and roller *s*, Fig. 2, consists of a flanged wheel with hub, a narrow flat ridge being raised at one end of the outer surface of flange, a narrow intervening 55 groove being provided between said ridge and the pinion-cogs, likewise situated at the outer surface of flange, these cogs engaging similar cogs on the circular piece *h* at the circumference of grate, the rail on *h* 60 bearing on the ridge formed on *s* and substituting one of the rim-rollers *c*, thereby obviating the necessity for an additional roller being placed near the pinion. The diameter 65 of the roller formed on *s* is made equal to the pitch diameter of the pinion, thus giving both roller and pinion parts the same velocity of travel. Suitable bearings are provided to

support the pinion-shaft *w* and brackets *y* for supporting the rim-rollers *c*, these being placed at proper intervals around the inside 70 of the furnace and, bearing against the rail on *h*, support the periphery of the grate.

It will be seen that the travel of the blast is unbroken from the blower through pipe *a* into post *b* and through the openings in *e* 75 into the hollow arms *g*, and thence into the hollow grate-bars *l*, and finally emerging at the various and numerous perforations in the hollow bars and central cover-plate.

By applying a moderate effort at the crank 80 *t* the grate will be rotated and any portion thereof brought opposite the fire-doors, as *o*, making it accessible from the outside.

What we claim, and desire to secure by Letters Patent, is as follows:

1. In a revoluble circular grate, segmental grate-bars, of hollow box-section, hollow branches projecting laterally at largest end of bars; perforations being provided at proper intervals along the upper corners of box and 90 branches, for the discharge of air-blast, said openings having an upward inclination toward outside of bar; each bar being provided with perforated blast-recesses, and covers *m* therefor, openings being provided at lower 95 side of bars for the introduction of air from hollow radial arms *g*, said openings having a faced jointing-strip all round, making air-tight joints with a corresponding strip on hollow arms when these are bolted together: 100 substantially as set forth.

2. In a revoluble circular grate a central hollow cylinder or hub *e*, said hub supporting at its outer surface, hollow radial arms *g*, said radial arms being bolted thereto, making air-tight joints; openings being provided for the 105 entrance of air-blast into said hollow arms; a grooved flange being provided at lower end of cylinder, said flange forming with a collar on post *d*, the receptacle for spherical bearing-rollers; inner surface at lower end of cylinder being recessed, said recess with projecting end of post *b* forming an air-tight movable joint: substantially as set forth.

3. In a circular revoluble grate, radial arms 115 forming at one end a hollow box with flange at open end, arms being bolted to a central cylinder *e* at corresponding air-passages therein, making therewith air-tight rigid joints; hollow branches projecting upward from each 120 side of box; said branches being connected rigidly to under sides of hollow grate-bars, opposite air-entrances therein, making air-tight rigid joints therewith; remaining portion of radial arms being of a T-section; a 125 foot being provided at lower edge of vertical web of T, said feet carrying a circular rack and rail and bolted thereto; horizontal web carrying circular rails supporting grate-bars: 130 substantially as set forth.

4. In a circular revoluble grate, the circular cover-plate *p* provided at outer edge with a cylindrical crown, said crown being perforated at intervals with blast-holes; an annu-

- lar space being provided between inner ends of grate-bars and outer edge of plate, allowing passage of air-blast; provision being made for rigidly attaching cover-plate to cylindrical hub e ; a hand-hole being provided at center of plate; a cylindrical crown being formed at edge of hand-hole, a continuous collar being formed near lower edge of crown at its inner surface; a notched collar situated above continuous collar at inner surface of crown, said collars constituting means for supporting and attaching hand-hole cover r : substantially as set forth.
5. In a circular revoluble grate, the circular hand-hole cover, r , said cover being formed of two parallel circular disks of unequal diameters, and radial webs perpendicular to the plane of and converging at the center of said disks, webs being notched, said notches fitting around a corresponding collar in the crown of hand-hole in cover-plate p for locking cover in place; projecting lugs being formed around
- the edge of larger disk to keep cover-plate centrally in position in hand-hole, and permitting passage of blast: substantially as set forth.
6. In combination with a circular revoluble grate, a pinion fixed at one end of a shaft, said shaft being supported by suitable bearings; pinion being provided with a projecting rim, diameter of said rim coinciding with pitch diameter of pinion-teeth; both rim and pinion-teeth corresponding to, and engaging with rim and rack-teeth forming part of circular rack and rail: substantially as set forth.
- 10 15 20 25 30 35
- In testimony whereof we have hereunto affixed our signatures in the presence of two subscribing witnesses.
